Term of patent 14 years

(Cl. D48—20)

FIGURE 1 is a top perspective view of a combined table lamp and cooler for bottles, or the like showing my new design.

FIGURE 2 is a bottom perspective view thereof.

FIGURE 3 is a fragmentary sectional view taken on line 3—3 of FIG. 4; and FIGURE 4 is a side elevational view thereof.

The dominant features of my design reside in the portions shown in full lines; said portions being characterized by the recessed top portion of the cooler which has a centrally located lamp support therein on which is mounted a lamp shade having a maximum diameter which is approximately equal to the width of the recessed top portion of the cooler together with the configuration of the upstanding molding on the top edge of the cooler as best indicated in FIGS. 1, 2 and 4.

I claim:

The ornamental design for a combined table lamp and cooler for bottles or the like, substantially as shown and described.
